UNITED STATES PATENT OFFICE.

GEORGE B. HAKINS, OF NORWOOD, NEW YORK.

IGNITING MECHANISM FOR EXPLOSIVE-ENGINES.

No. 892,253.

Specification of Letters Patent.

Patented June 30, 1908.

Application filed February 5, 1906. Serial No. 239,592.

To all whom it may concern:

Be it known that I, GEORGE B. HAKINS, a citizen of the United States, residing at Norwood, in the county of St. Lawrence and 5 State of New York, have invented new and useful Improvements in Starting and Igniting Mechanism for Explosive-Engines, of which the following is a specification.

My invention relates to improvements in 10 starting and igniting mechanism for explosive engines which is especially intended for use in connection with explosive-engines for driving vehicles.

As is well understood by those skilled in 15 the art, explosive-engines in which the speed is varied requires also a variation of the point or period of the ignition of the explosive charge relative to the position of the piston and its driven crank. When an explosive 20 motor is running at high speed, the point of ignition is just in advance of the driven crank reaching its dead center. It is also well understood that in explosive-engines it is necessary to start the engine by giving a sufficient movement thereof to cause one explosion. 25 In explosive-engines, therefore, used for driving vehicles in which the point of ignition must vary according to the speed of the engine and in which also the engine must be started by hand it is necessary to provide 30 means whereby the operator cannot, without gross carelessness, attempt to start the engine when the sparkler is set to ignite the charge at a point in advance of the crank 35 reaching the point of dead-center; for otherwise the operator is liable to injury because of the back motion of the engine in causing the ignition of the charge before the dead-center is reached. Also in engines of the explosive type when used in connection with 40 motor-vehicles a ratchet starting-lever is used, by means of which the engine can be moved forward and when started the ratchet will permit the engine to revolve without affecting or moving the starting mechanism. 45 Should however, the engine run backward, the ratchet would hold and cause injury to the operator.

Keeping in mind the above explanation, 50 the object of my present invention is to provide a safety device whereby the operator is unable to bring into action the ignition instrumentalities connected with such engine until he has first moved the device for timing 55 such ignition to its latest point of ignition

with relation to the motion of the engine piston.

In the accompanying drawings Figure 1 is a perspective view of one form of my invention adapted to be used upon a motor vehicle in which the time of ignition by electric spark is controlled by an oscillating crank; but in which view the size of switch mechanism is exaggerated in proportion to said crank. Fig. 2 is a perspective view showing 60 my invention applied to a motor vehicle.

However I do not wish to limit myself to the specific mechanism herein shown, as it is apparent that such mechanism may be varied to adapt it to the different forms of ignition controllers in use with different explosive engines, without departing from the spirit and scope of my invention, which is to compel the operator to first bring the controller of such ignition device to the position of the latest period for firing, before such ignition instrumentalities can be made operative, thereby guarding the operator against the dangers of premature explosive or "back motion" as above explained.

In the accompanying drawings A indicates the spark controlling hand crank of the form usually employed on motor vehicles; a' represents the crank shaft connected therewith, which shaft extends downward, inclining forward, through the vehicle body, to which it is rotatively secured by any of the customary means, and provided at or near its lower end with a crank a² projected in a direction similar to crank A and pivotally connected to the spark timing rod a³, which rod is similar in all respects to that customarily employed on electric sparking motors and is connected at its further end with the customary spark controlling and ignition instrumentalities represented at H in Fig. 1. a⁴ represents a portion of the rack usually employed to lock crank A in any part of its course, by means of the customary spring detent a⁵, on said crank A, with the blank extension there-to required to permit the further and free motion of said crank to operate the switch mechanism hereinafter explained. Above the vehicle floor, a collar B is attached rigidly to said crank shaft a' having a stud b' ex-tending outwardly from the collar, adapted to engage with the swinging lever C loosely fulcrumed upon said crank shaft by means of an eye in the end of said lever. Near the middle of said lever is attached a tensile 110

spring c' , which at its other end is fastened to the switch-platform D. At its outer end said lever C is hinged to the vibrating beam e, which is slidingly held to the said platform D by means of headed studs d' , d'' , passing through longitudinal slots in said beam and made fast to said platform. On a projection of said beam e, on the side opposite to the said lever C, is rigidly attached a bayonet spring e' , projected toward a binding-post headed stud d^2 , attached to said platform D, upon which stud is pivotally hung the switch-bar F, the body of which is made of non-electric-conducting material, and is provided with a tooth f' projected toward said spring e' , and having notches at both sides of its base for the purpose hereinafter explained. At the outer extremity of said bar F, is attached the arm f^3 carrying the indicator f^4 for the purpose hereinafter explained, and on the underside of said bar F and near its outer extremity is attached a switch point f^2 (shown by dotted lines) electrically connected to the stud binding post d^2 for purposes hereinafter shown. Attached to the upper face of said platform D, in such position as to coincide with said switch-point on the bar F when the latter reaches the limit of its travel in one direction, is the switch-point d^3 electrically connected to the engine spark. And also projecting from the upper face of said platform D are the two pins d^4 and d^5 to limit the motion of the switch bar F on either side.

G represents an arched flat spring inserted between the head of stud d^2 and the body of switch bar F to retard the free motion of the latter.

This rack may be attached to the steering mechanism in the manner usual on motor vehicles.

In operation, the spark controlling crank and shaft having been placed on the vehicle in its usual position near the steering wheel with the electric switch mechanism forward thereof and made fast to the platform of such vehicle, the binding post d^2 is electrically connected with the battery, or other source of electricity carried upon said vehicle, while the point d^3 is also electrically connected therewith through the sparking instrumentalities of the engine, and the switch-bar F being placed in the position shown by the full lines, it is manifest that the electric circuit is broken by the non-contact of the point d^3 with the point f^2 on the underside of the switch bar F, heretofore described, and that therefore no sparking can then take place in the engine. Now, by moving the spark controlling crank toward the right to the late spark position, the stub b' upon the collar B, will be brought into contact with the side of the lever C, and further motion thereof in the same direction to its full limit will, through the movement of such lever, C, draw forward the beam e, with its attached

bayonet-spring e' , which, sliding on the forward inclined surface of the tooth f' , will catch in the notch at the base thereof and thereby swing the switch bar F, upon its pivot d^2 , until it is brought into the position shown by the broken lines and the two switch points are brought into contact with each other, thereby establishing an electric circuit through the spark and at the same time throwing the indicator f^4 into view beyond platform D. As soon as the engine is in full operation, that detent may be released and the spark timed forward, as is usually done, by advancing the spark-controller crank toward early sparking position at the left-hand end of this sector a^4 , without in anywise disarranging or interfering with, said switch mechanism. When it is desired to again disconnect the said electric current the spark controller crank is first brought to the late sparking position on the right hand end of said sector and its motion continued further towards the right and beyond the arresting teeth of said sector, when through the connected mechanism above explained, the bayonet spring is again advanced toward and slid on the opposite side of tooth f' into the corresponding base notch on that side of said tooth, thereby throwing the switch bar into its original position, withdrawing the indicator f^4 from sight and disconnecting the switch-points above described; thus leaving the ignition instrumentalities, above described, inactive until the spark controller crank is again first brought to the late-spark position on the sector a^4 .

Having thus explained the nature of my invention and described one way of constructing and using the same, but without attempting to set forth all the forms in which it may be made or used, what I claim and desire to secure by Letters Patent is

1. In combination with an explosive engine having an igniting device, means by which the firing of the explosive mixture can be advanced or retarded with relation to the position of the piston of such engine, and other means for putting such igniting device entirely in or out of operation dependent upon the prior movement of such first means to the position for retarding such firing.

2. In combination with an explosive engine, instrumentalities for producing a spark for firing the explosive mixture therein, switch mechanism for throwing such instrumentalities into or out of operation, and means for actuating such switch mechanism dependent upon the prior movement of the said instrumentalities to the position of retarding the firing of such spark with relation to the position of the piston of such engine.

3. In combination with an explosive engine, an igniting device the firing of which can be advanced or retarded with relation to the position of the piston of such engine,

means including a hand crank, for so advancing or retarding such firing, and other means for putting such igniting device entirely in or out of operation dependent upon the prior movement of such hand crank to the position for retarding such firing.

4. In combination with an explosive engine an igniting device comprising means for producing an electric spark, the firing of which can be advanced or retarded with relation to the position of the piston of such engine, means including a hand crank for so ad-

vancing or retarding such firing, and other means for putting such igniting device entirely in or out of operation dependent upon the prior movement of such hand crank to the position for retarding such firing.

In testimony whereof I have signed my name to this specification in the presence of two subscribing witnesses.

GEORGE B. HAKINS.
